United States Patent Office.

THOMAS STONE, OF PLAINFIELD, INDIANA.

Letters Patent No. 71,813, dated December 3, 1867; antedated November 23, 1867.

IMPROVED BRICK-MACHINE.

The Schedule referred to in these Letters Patent and making part of the same.

TO ALL WHOM IT MAY CONCERN:

Be it known that I, THOMAS STONE, of Plainfield, in the county of Hendricks, and State of Indiana, have invented a new and improved Brick-Machine; and that the following description, taken in connection with the accompanying drawings, hereinafter referred to, forms a full and exact specification of the same, wherein I have set forth the nature and principles of my said improvements, by which my invention may be distinguished from all others of a similar class, together with such parts as I claim and desire to have secured to me by Letters Patent.

This invention relates to a new and improved machine for moulding and pressing bricks, and it consists of a novel arrangement of means for operating the moulds and pressing the clay therein, and also in a means for sanding the clay, all the parts being so constructed and arranged that the clay is tempered, forced into the moulds, and pressed, and the filled moulds discharged from the machine by the rotation of a single shaft, to wit, the mud-mill shaft. In the accompanying sheet of drawings—

Figure 1 is a side-sectional view of my invention, taken in the line *x x*, fig. 2.

Figure 2, a vertical central section of the same, taken in the line *y y*, fig. 1.

Similar letters of reference indicate like parts.

A represents a rectangular frame, which may be constructed in any proper manner, to support the working parts, and B is a case or box, of cylindrical or other form, which is secured on the frame A, and has a vertical shaft, C, passing centrally through it, and extending down to the bottom of frame A, where it is stepped, as shown at *a*. To the upper end of the shaft C there is attached a sweep, D, to which the horse or team is connected, and this shaft C is provided with radial arms *b*, which serve to mix and temper the clay, the two lower arms *b* serving as pressers to force the clay down through tubes E to the moulds F. (See fig. 1.) Each tube E is provided with a slide, *c*, by adjusting which the supply of clay to the moulds may be regulated as desired. On the shaft C, directly underneath the bottom *d* of the mud-mill, there is keyed a bevel-wheel, G, which gears into two similar wheels, H H, on the ends of the inner journals of two rollers, I I, the wheels H H being at opposite sides of the wheel G, as shown in fig. 2. The rollers I I are fitted transversely in boxes J J, placed longitudinally in the frame A, one at each side thereof, and at each end of each roller there are friction-toothed rims *d* to gear into racks *e* on each side of the top of the moulds F. These moulds F work on friction-rollers K, which are placed in the bottoms of the boxes J J, and are designed to insure the free or easy movement of the moulds F in their passage through the boxes J. The friction-rollers are fitted in frames L, which rest on India-rubber or other suitable springs, *f*, shown in both figures. In each box J there is placed an inclined chute, M. These chutes extend to the rollers I I, and just clear, or are not quite in contact with them, and they form the bottoms of sand-boxes, by which the tops of the bricks or compressed clay in the moulds are properly sanded.

The clay, properly moistened, is thrown into the upper end of the mud-mill, and the shaft C, being rotated by the horse or team which is attached to it, the clay is properly tempered by the action of the arms *b*, the lower arms *b* forcing the clay down the tubes E to the moulds F, in which it is compressed by the rollers I, the motion to which is given by the gearing G H H from the mud-mill shaft C. The moulds are fed through the boxes J J by the toothed rims *d* on the rollers I I, gearing into two racks *e* on the moulds, the filled moulds being discharged on opposite sides of the frame A, and the empty moulds placed in said frame at opposite sides, a man being at each side of the machine during the operation of the same, in order to insert empty moulds, and take the filled ones therefrom.

In consequence of having the roller-frames L resting on springs *f*, the moulds F are allowed to yield or give, should stones or any foreign substance enter them with the clay, and project above the level of their upper surfaces. By this simple provision the working parts of the machine are relieved of all strain to which they would otherwise be subjected in case of the contingency above alluded to occurring.

Having thus described my invention, I claim as new, and desire to secure by Letters Patent—

1. The rollers I I operated from the mud-mill shaft C by means of the gearing G H H, in combination with the moulds F, operated from the rollers I I by the toothed rims *d* and racks *e*, all arranged substantially as and for the purpose described.

2. The roller-frames L, carrying their moulds, when placed on springs *f*, when used in connection or combination with the rollers I I, substantially as and for the purpose set forth.

The above specification of my invention signed by me, this 8th day of March, 1867.

THOMAS STONE.
